Specification for Design.

Patented Nov. 22, 1921.

Application filed May 23, 1921. Serial No. 471,993. Term of patent 14 years.

To all whom it may concern:

Be it known that I, WILLIAM M. PARKER, a citizen of the United States, and resident of Parkersburg, in the county of Wood and State of West Virginia, have invented a new, original, and ornamental Design for a Plural Socket, of which the following is a specification, reference being had to the accompanying drawing, forming part thereof, in which—

Figure 1 is a top plan of a plural socket embodying my new design;

Fig. 2 is an elevation of the same; and

Fig. 3 is a bottom plan of the same.

What I claim is:

The ornamental design for a plural socket, as shown.

WILLIAM M. PARKER.
